By his Attorney,
Nelson W. Howard

UNITED STATES PATENT OFFICE.

JAMES CAVANAGH, OF BOSTON, MASSACHUSETTS, ASSIGNOR TO UNITED SHOE MANUFACTURERY CORPORATION, OF PATERSON, NEW JERSEY, A CORPORATION OF NEW JERSEY.

LAST.

Application filed April 17, 1919. Serial No. 290,674.

To all whom it may concern:

Be it known that I, JAMES CAVANAGH, a citizen of the United States, residing at Boston, in the county of Suffolk and State 5 of Massachusetts, have invented certain Improvements in Lasts, of which the following description, in connection with the accompanying drawings, is a specification, like reference characters on the drawings indicating like parts in the several figures.

This invention relates to boot and shoe lasts and the invention is herein illustrated as embodied in a separable last comprising fore and heel parts relatively movable to 15 collapse the last.

In the manufacture of shoes by machinery it is customary to employ different kinds of lasts according to the particular method of manufacture employed. For instance, when 20 the method involves attaching the heels by inside nailing, the lasts employed usually have removable heel parts, or are bodily removed for the purpose and when the method involves outside heel nailing, it is customary to employ lasts the fore and heel 25 parts of which are not separated in use, but have a hinged or swinging connection to permit easy removal of the last when desired. In either case, it may be desirable 30 to vary the length of the lasts for reasons so well known as to require no detailed explanation herein.

An important feature of my invention is a last having fore and heel parts provided 35 with separable hinged, extensible connections, whereby it can be employed in the manufacture of shoes according to either of the above-mentioned methods, and can be extended while in the shoe to properly 40 stretch the upper over the forepart, the particular advantage of this last being that a single line of lasts instead of a plurality will serve for the different methods.

The illustrated construction embodies fore 45 and heel parts of the last provided with an adjustable hinge, by which I mean a hinge the pivot of which can be set at different distances from the toe of the forepart, whereby the total or bodily length 50 of the last may be increased.

In the particular embodiment the invention illustrated, the fore and heel parts are

so connected that the length of the last may be gradually increased by a rocking or oscillating movement of a tool.

These and other features of the invention comprising certain arrangements and combinations of parts will be explained in the following specification and pointed out in the claims.

In the drawings, which show a preferred embodiment of my invention,

Fig. 1 is a side elevation, partly in section, of the last in its collapsed or shortened condition;

Fig. 2 is a similar view illustrating the operation of shifting the connections in one of the steps performed for effecting a lengthening of the last; and

Fig. 3 is a similar view illustrating a further step in the lengthening of the last.

The fore part 12 and heel part 13 are of any suitable last form, each having a recess to contain the connections. Mounted on a pivot pin 14 extending transversely 75 of the recess in forepart 12 is a bell-crank lever latch comprising a finger-operated portion 15 and a pawl or latch portion 16. A bar 17 having a series of notches 18 in its upper surface or edge is slidably mounted in a recess or socket 19 in the forepart 12, said bar having a pin 20 extending laterally from one or both sides thereof. A locking plate 21 which forms an adjusting locking lever is pivotally mounted on 85 a pin 22 extending transversely of the recess in heel part 13, said plate having a forked arm 23 engaging the pin or pins 20 of bar 17. Said plate is also formed with a substantially vertical socket 24 having a 90 hole 25 at its inner end (see dotted lines, Fig. 2). A bolt 26 mounted in a recess in the heel part and normally ejected by a spring 27 is adapted to engage the hole 25 to lock the plate 21 in the position indicated in Fig. 1.

Any suitable tool 28 as for example, a jack pin, having a reduced tip portion 29 adapted to pass through the hole 25 of socket 24 may be employed to unlock the 100 plate 21, as indicated by comparing Figs. 1 and 2. When such tool is inserted in the socket far enough to press the bolt 26 into its socket so as to clear the lower end

of the socket 24, such tool may then be employed to rock or oscillate the plate 21 on its pivot 22.

A latch arm 30, pivoted at 31 to the heel part 13, is formed with a series of notches 32 in its lower surface or edge, either one of said notches being adapted to engage a small pin 33 extending transversely of the recess in the forepart 12. The latch 30 may 5 be manually lifted out of engagement with the pin 33 and to facilitate such operation it is preferably provided with a finger piece 34.

In operation, assuming that the last is in 15 its shortened condition indicated in Fig. 1 and is to be lengthened or extended, the operator inserts the tool 28 in the socket 24 far enough to cause the tip 29 to release the bolt 26 from the hole or keeper 25. He then 20 operates the tool to swing the plate 21 to or toward the position indicated in Fig. 2, thereby drawing the bar 17 rearwardly so that, although the heel part is not yet shifted relatively to the forepart, yet the pivot pin 25 20, which co-acts with the yoke or fork 23 to form a hinge, is shifted to a point farther from the secant face of the forepart. The latch member 15, 16 of course readily yields automatically to permit this withdrawal or 30 rearward movement of the bar 17 and the hinge pindle 20. Upon then returning or actuating the tool 28 in the reverse direction so as to carry the plate 21 to the Fig. 3 position, the bar 17 remains in its partially withdrawn 35 position so that the members 20, 23 will act as a fulcrum while the plate 21 and the parts carried thereby are moved from the Fig. 2 position to the Fig. 3 position, the latch 30 readily moving over the pin 33 to 40 the position shown in said Fig. 3. By continuing these operations of rocking the plate 21, the last may be extended to any length permitted by the series of notches 18 in the bar 17 and 32 in the latch member 30. Of 45 course, in practice these notches may be smaller ones than illustrated in the drawings to permit finer adjustments.

I do not illustrate springs for holding the latch member 15, 16 and the latch member 30 50 in engaged positions, but it will be readily understood that any suitably mounted springs may be employed for such purpose.

By depressing the bolt 26 to release the pivotally mounted member 21, the heel part 55 may be extended relatively to the forepart by pressing down upon the forepart when the last is in an inverted position from that shown in the drawings, the parts then being held in their new position by the engagement of the toe or latch 16 with the notched bar 17. Then when the forepart is swung or returned to its position for use, the other latch member 30 automatically moves into proper locking position, the bolt 26 automatically returning to position to lock the plate 60 65

21. Then in order to collapse the last or shorten it, it is only necessary to swing the latch member 30 upwardly to disengage it from the pin 33 and swing the elbow lever 15, 16 to disengage the latter portion from the notched bar 17 and then simply slide the two parts toward each other.

Since the pin 20 of the bar 17 co-acts with the yoke or fork 23 to form a hinge, the last 75 may be operated like an ordinary hinged last by simply disengaging the upper latch 30 from its pin 33, and this may be done regardless of whether the location of the hinge pindle is nearer to or farther from the secant face of the forepart.

The parts of the last are readily separable while in the shoe by simply pulling them apart, the latch member 30 then riding over the pin 33 and the bar 17 pulling directly out from the socket in the forepart.

It will now be understood that I have provided a last which is extensible in what may be called a straight line, the heel part being bodily extensible while the sole faces of the two parts remain in alinement, that is, without shifting one part angularly relatively to the other part. Also, the members are capable of use as a hinged last and are quickly separable, and the last may be employed on the usual jack support entering the socket 23. 90

I do not limit myself to the use of the device as a last for the manufacture of boots or shoes, since a similarly constructed device may be employed either for the repairing of boots or shoes or as a form for keeping a shoe in shape.

Having now described my invention in a preferred embodiment thereof, what I claim is:—

1. A last comprising fore and heel parts 105 having longitudinally adjustable connections, whereby the operative length of the last may be substantially varied, constructed and arranged to hold the last against collapse, said connections being readily separable in the use of the last.

2. A last comprising fore and heel parts having separable and longitudinally adjustable connections, said connections comprising strut members constructed and arranged 115 to permit free removal of the heel part or to hold the heel part separated from the forepart in any desired position.

3. A last comprising fore and heel parts provided with hinged, extensible connections, arranged to support the parts positively under compressive stresses tending to collapse the last, said connections being readily separable in the use of the last.

4. In a last having separate fore and heel parts, a plurality of members one above another extending from one to the other of said parts, and engaging them both at points having a substantial vertical separation, and means for longitudinally adjusting said 120 125 130

members to vary substantially the length of the last as a whole.

5. A last comprising fore and heel parts having a hinge connection, the length of 5 which is adjustable over a substantial range, and a locking member constructed and arranged to hold the last in longitudinally extended position throughout the range of adjustment.

10 6. A last comprising a forepart having a hinge member adjustable relatively thereto over a substantial range to vary the size of the last, a heel part having a cooperating hinge member, and a locking member similarly adjustable to hold the last in operative position throughout the adjustment.

15 7. A last comprising a forepart having a notched bar adjustable therein, said bar having a hinge member at its outer end, a heel 20 part having a co-operating hinge member, and a latch carried by the forepart to engage the notches of said bar.

25 8. A last comprising a forepart having a notched bar adjustable therein and a latch to co-operate with the notches thereof, said bar having a hinge member, and a heel part having a co-operating hinge member, means being provided to actuate said co-operating member of the heel part to draw said bar 30 out from the forepart.

35 9. A last comprising a forepart having a notched bar provided with a pin at its outer end, a latch to engage the notches of said bar, a heel part having a pivoted plate provided with a fork engaging the pin of said notched bar, said plate having a socket for a tool to enable said plate to be rocked on the pivot, and means for locking said plate against oscillation.

40 10. A last comprising a forepart having a notched bar provided with a pin at its

outer end, a latch to engage the notches of said bar, a heel part having a pivoted plate provided with a fork engaging the pin of said notched bar, said plate having a socket 45 for a tool to enable said plate to be rocked on the pivot, and means for locking said plate against oscillation, said locking means comprising a spring bolt mounted in the heel part and a keeper for said bolt carried 50 by the hinged plate.

11. A last comprising fore and heel parts having hinged connections constructed and arranged to co-operate to prevent relative rotation of said parts when in adjusted position, said connections being adjustable to vary the effective length of the last over a 55 substantial range.

12. A last having freely separable fore and heel parts and having adjustable means 60 for preventing relative approach beyond a desired point, constructed and arranged to hold the parts against collapsing movement.

13. A last comprising fore and heel parts having two connecting devices each forming 65 an abutment upon which the parts can be rocked to permit extension of the other.

14. A last comprising fore and heel parts having extension mechanism consisting of a plurality of alternately acting ratchet devices. 70

15. A last comprising fore and heel parts, a plurality of notched members extending between said parts, means for co-acting with the notches of said members to hold the last 75 parts in extended positions, and means for shifting said notched members longitudinally.

In testimony whereof I have signed my name to this specification.

JAMES CAVANAGH.
